No. 14,488

DEC 18, 1883

UNITED STATES PATENT OFFICE.

H. CLAY BASCOM, OF TROY, NEW YORK, ASSIGNOR TO N. S. VEDDER PATTERN WORKS, BASCOM, GALBRAITH & CO., OF SAME PLACE.

DESIGN FOR A COOKING-STOVE.

SPECIFICATION forming part of Design No. 14,488, dated December 18, 1883.

Application filed November 3, 1883. Term of patent 7 years.

To all whom it may concern:

Be it known that I, H. CLAY BASCOM, a citizen of the United States, residing in the city of Troy, in the county of Rensselaer and State 5 of New York, have invented and produced a new and original Design for Cooking-Stoves, of which the following is a specification, reference being had to the accompanying cut, print, or engraving, representing my said new 10 design.

My design for the side of the stove-body consists of the oven-door A and fire-box door or panel B, shaped, ornamented, and arranged on the plate C so as to present substantially 15 the same appearance as is represented in the aforesaid print.

The design for the front of the stove consists of the fire-door D and plate E, shaped, ornamented, and arranged together substantially 20 as shown in the aforesaid cut.

The design for the side plate, F, of the rear extension consists of the panel B', reversely-curved lower edge part, a, and compound ornament b, shaped and arranged substantially 25 as shown in said engraving.

The design for the oven-door A consists of the sunflower ornament c and outer ornamentation d, shaped and arranged together substantially as shown.

The design for the door or panel B or B' consists of the star flower ornament e and outer ornamentation, f, shaped and arranged together substantially as shown.

The design for the front door, D, consists of 35 the series of mica light-apertures g and intervening ornaments, h, over the row of draft-openings i and intermediate ornaments, j, all shaped and arranged together substantially as shown.

The design for the front plate, E, consists of 40

the two raised panels k, each having thereon the central star ornament z, and upper and under ornaments, m m', all shaped and arranged as shown.

The design for the legs consists of the convex surface n, having the central star ornament o, outer ornament, p, and curved downwardly-converging side edges, q, all shaped and disposed substantially as shown. 45

I claim as my invention—

1. The design for the side of the stove-body, composed of the parts A B C, shaped, ornamented, and arranged as shown and described.

2. The design for the stove-front, consisting of the parts D E, shaped, ornamented, and arranged as set forth. 55

3. The design for the side plate, F, of the rear extension, composed of parts B' a b, as set forth.

4. The design for the oven-door A, composed of the ornamental parts or figures c d, as set forth. 60

5. The design for the door or panel B or B', composed of the parts e and f, as shown and described.

6. The design for the front door, D, consisting of the parts g h and i j, as shown and described.

7. The design for the front plate, E, composed of the parts k l m m', as shown and described. 70

8. The design for the legs, composed of the parts n o p q, as shown and described.

In testimony whereof I hereunto set my hand, in the presence of two subscribing witnesses, this 1st day of November, 1883. 75

H. CLAY BASCOM.

Witnesses:

CHARLES H. BENEDICT,
CHESTER BASCOM.
